HYDRAULIC GATE OPERATING
MECHANISM

Arthur Young, York, Pa., assignor to S. Morgan
Smith Company, York, Pa., a corporation of
Pennsylvania

Application September 9, 1938, Serial No. 229,069

6 Claims. (Cl. 61—22)

This invention relates to hydraulic gates and more particularly to operating mechanism therefor.

An object of the invention is to provide an improved operating mechanism for hydraulic gates of the type known as tainter gates, by which the gates may be raised and lowered by means of hoisting mechanism adapted to travel lengthwise of the dam structure.

10 Dam structures of the type now constructed for hydro-electric purposes include in a portion of their length a series of spillways which are separated by piers. The piers may be spaced apart any suitable distance. However, in most cases the spaces between the piers are from thirty to forty feet. The piers extend upwardly a suitable height above the crest of the dam, and in order to increase the depth of the water on the upstream side of the dam a gate is pivotally mounted in 15 the opening between each of the piers. A suitable distance upstream from the front wall of the gates, the piers are formed with vertical slots, which slots are adapted to receive horizontally disposed stop logs. The stop logs are formed 20 from heavy timber and these elements are adapted to overlie one another when in position in the dam.

Usually the stop logs are inserted in the dam when it is desired to repaint, repair or inspect the 25 pivoted gates, and in order to enable the stop logs to be easily placed in position in their slots and to be quickly removed therefrom, the top of the dam structure has mounted thereon tracks for a gantry crane or other suitable traveling 30 hoisting mechanism. The tracks are mounted on beams supported by the piers of the dam and overlie the stop log slots and the front portion of the pivoted gates.

Heretofore, so far as I am aware of, separate 35 mechanism was provided for operating the tainter gates. By the present invention, the construction has been improved so that the same mechanism which is used for lowering and raising the stop logs can be employed to operate the tainter 40 gates.

With the foregoing and other objects and advantages in view, the invention consists in the construction and arrangement of the several parts which will be hereinafter more fully described 45 and claimed.

In the accompany drawings:

Figure 1 is a plan of a portion of a dam structure embodying the present invention;

Fig. 2 is a vertical transverse section taken on 50 the line 2—2 of Fig. 1;

Fig. 3 is a vertical transverse section taken on the line 3—3 of Fig. 1;

Fig. 4 is a vertical longitudinal section taken on the line 4—4 of Fig. 3;

Fig. 5 is an enlarged vertical section of a portion of the structure shown in Fig. 4;

Fig. 6 is an enlarged view of a portion of the structure shown in the upper part of Fig. 2; and

Fig. 7 is a horizontal section taken on the line 10 7—7 of Fig. 6.

Referring to the drawings, the dam 11 comprises a crest 12, upon which is adapted to rest the lower edge 13 of a tainter gate 14.

The gate 14 is formed of a structural steel framework, carrying at its front end an arcuate 15 wall 15 preferably formed from plate steel or the like. The framework of the gate 14 includes rearwardly extending arms 16, each of which carry at their extremity a journal 17 which is mounted on a pivot pin or trunnion 18 carried by the pier 20 19 of the dam.

In the drawings two piers 19 are shown. It will be noted, however, that the dam may be of any length and have as many piers as desired.

As shown in Fig. 2, the top of each pier 19 is 25 somewhat higher than the crest 12 of the dam. Also the top of the piers overlies the upper edge of the gate 14 a considerable distance when the gate is in its lowermost position.

At a suitable distance upstream from the front 30 wall 15 of the gate 14, a vertical slot 20 is formed in the side wall of each pier. These slots 20 are adapted to receive the ends of stop logs 21, one of said logs being indicated by broken lines in Fig. 1.

Supported by the upper portions of the piers 35 19 is a pair of beams 22 and 23, upon which are respectively mounted rails 24 and 25 of a track.

The rails 24 and 25 are spaced apart a suitable distance so as to receive the wheels 26 of a gantry 40 crane 27.

The crane 27 is adapted to travel lengthwise of the dam and said crane comprises a skeleton framework which supports hoisting mechanism mounted within a car 28.

The car 28 is movably mounted on the crane 27 in well known manner, and suspended therefrom by cables 29 is a lifting beam 30.

As shown in Figs. 4 and 5, the lifting beam 30 comprises a skeleton framework which carries a 50 series of depending hooks 31 and 32, the hooks 31 being disposed in the end portions 33 of the lifting beam 30 and the hooks 32 being disposed intermediate of the beam for a purpose which will be hereinafter described.

Fastened to and projecting upstream the front wall 15 of the gate 14, is a pair of lugs 34. These lugs are located adjacent the ends of the gate.

Pivoted connected by a pin 35 to each lug 34, 5 is the lower portion of a vertically disposed arm 36. As shown in Fig. 7, each arm 36 may be formed from a structural steel H beam of suitable length to extend upwardly toward the top of the pier 19 when the gate 14 is in its lowermost position.

In order to prevent lateral displacement of each arm 36, the pier 19 supports a rectangular bracket or loop 37, preferably formed from structural steel members embedded in the masonry of the pier, as shown in Fig. 7.

The bracket or loop 37 is somewhat larger in area than is the size of the arm 36 in cross section, so as to permit free movement of the arm when the gate 14 is being raised and lowered. 20 However, in order to limit the movement of the upper portion of the arm 36 within the bracket or loop 37 preparatory to the operation of raising the gate 14, the arm 36 is formed with a cam member or lug 38 which is disposed within the bracket or loop 37 when the gate is in its lowermost position.

Near its upper end the arm 36 is formed with an opening 39 of a size adapted to receive the bent or hooked end of the lifting beam hook 31, 30 as shown in Fig. 5.

The portion of the pier 19 to which is mounted the bracket or loop 37 is formed with a recess 40 so that the lifting beam 30 can be lowered to the position where the hooks 31 can be inserted in the openings 39 of the two arms 36 of each gate.

Wheels 41 are mounted on each end of the lifting beam 30. These wheels are adapted to engage the opposite side walls of the stop log slots 20 when the crane 27 is employed for removing and placing stop logs in the dam.

Mounted in the end portions 33 of the lifting beam 30, are wheels 42 which are adapted to engage the edges of the arms 36 when the lifting beam 30 is secured to said arms, as shown in Fig. 5.

Each hook 31 has one end pivotally connected to the lifting beam 30, as indicated at 43, Fig. 5. Below the pivot 43, the hook 31 is formed with a cam 44 which is adapted to engage the upper end of the arm 36 in such a manner that the hook will be disconnected from the arm when the lifting beam 30 is lowered a suitable distance below the position shown in Fig. 5.

Connected to the upper end of the hook 31 is one end of a link 45. The other end of the link 45 is connected to a lever 46 pivotally connected to the lifting beam 30, as at 47. The lever 46 extends upwardly and terminates above the top of the lifting beam. The relative position of the upper end of the lever 46 with respect to the lifting beam 30 indicates to an operator the position of the hook 31 with respect to the upper end of the arm 36. Lever 46 may be operated when so desired to move the hook 31 into and out of engagement with the opening 39 in the arm 36.

In order to support the gate 14 in raised position, each arm 36 is formed with a bar or lug 48 (see Figs. 2 and 6). The lug 48 is secured to the lower portion of each arm 36, so that when the gate 14 has been raised a predetermined amount, the lug will engage a latch or dog 49 mounted on the bracket or loop 37.

In operation, assuming that the gates 14 of a dam are down and it is desired to raise same, the gantry crane 27 is moved along the track

to a position over one of the gates. The car 28 is then moved to the position in which the lifting beam 30 overlies the arms 36 of the gate. The lifting beam 30 is now lowered to the position shown in Fig. 4 and the hooks 31 operatively 5 connected with the arms 36, as shown in Fig. 5.

The hoisting mechanism (not shown) of the lifting beam 30 is now operated to pull the lifting beam upwardly an amount sufficient to engage the dogs 49 with the bars or lugs 48, as 10 shown by dotted lines in Figs. 2 and 6.

The hooks 31 can now be detached from the arms 36, and the lifting beam 30 elevated a distance to provide traveling clearance so that the crane 27 can be moved to the next gate to be 15 raised. The operation is then repeated until all of the gates of the dam have been raised.

When it is desired to lower the gates, after the hooks 31 of the lifting beam 30 have been connected to the arms 36, the lifting beam is 20 raised a slight distance to enable the dogs or latches 49 to be moved away from the lugs 48. The lifting beam is now lowered to the position in which the lower edge of the gate 14 rests on the crest 12 of the dam. The hooks 31 of the 25 lifting beam 30 are then disconnected from the arms 36 and the lifting beam elevated sufficiently to provide traveling clearance so that the crane 27 can be moved to the next gate to be lowered. The operation is then repeated.

From the foregoing it will be noted that by the present invention I have provided an improved hoisting mechanism for hydraulic gates in which the use of cables, chains, and individual operating mechanism therefor, heretofore commonly used for operating such gates, has been eliminated. In their place there is employed simplified mechanism which is adapted to be selectively operated by a single gantry crane of the type usually installed on the dams for the purpose of installing and removing the stop logs.

Having thus described my invention, what I claim is:

1. The combination with a structure having an opening with vertical side walls, a rotatable gate 45 for closing said opening, a vertically disposed arm pivotally connected at each end of said gate, a bracket projecting from each side wall, said arm projecting through said bracket, means engageable with said arms for raising and lowering the 50 gate, and means carried by said brackets for engaging said arms when the arms have been raised a predetermined distance for retaining the gate in raised position.

2. A dam structure comprising a pair of up- 55 standing piers and an opening therebetween, a gate rotatably supported by the piers for closing said opening, a vertically disposed arm pivotally connected at each end of the gate, a bracket projecting from each of said piers for limiting the 60 swinging movement of said arms, a beam structure having hooks engageable with said arms for raising and lowering the gate, and means carried by said brackets and engageable with said arms 65 for retaining said gate in raised position.

3. In combination with a water gate, a vertical- 70 ly disposed arm pivotally connected at one end to said gate, the free end of said arm projecting upwardly from the gate, means for limiting free swinging movement of said arm, lifting mechanism engageable with the upper free end of said arm for lifting said arm and the gate secured thereto upwardly, said arm being movable upwardly in a substantially vertical path, and a 75

latch engageable with said arm for retaining the gate in raised position.

4. In combination with a water gate, a vertically disposed arm pivotally connected at one end to said gate, the free end of said arm projecting upwardly from the gate, means for limiting free swinging movement of said arm, lifting mechanism engageable with the upper free end of said arm for lifting said arm and the gate secured thereto upwardly, and a latch carried by said limiting means and engageable with said arm for retaining the gate in raised position.

5. In combination with a water gate, a substantially vertically disposed arm pivotally connected at one end to said gate, the free end of said arm projecting upwardly from the gate, means for limiting free swinging movement of said arm with respect to the gate, detachable lifting means engageable with the upper free end of said arm

for lifting said arm and the gate secured thereto upwardly, and a latch carried by said limiting means and engageable with said arm for retaining the gate in raised position so as to permit detachment from the arm of said lifting mechanism.

6. In combination with a water gate, a substantially vertically disposed arm pivotally connected at one end to said gate, the free end of said arm projecting upwardly from the gate, a fixed bracket encircling the arm for limiting free swinging movement thereof, detachable lifting means engageable with the upper free end portion of said arm for lifting said arm and the gate secured thereto upwardly, a lug projecting from said arm, and a latch carried by said bracket and engageable with said lug for retaining the gate in raised position.

ARTHUR YOUNG.
